PROCESS OF AND APPARATUS FOR THE
MANUFACTURE OF ARTIFICIAL RIBBONS,
ETC.Rudolf Etzkorn, Oberbruch, Regierungsbezirk
Aachen, Germany, assignor to North American
Rayon Corporation, New York, N. Y., a corpo-
ration of DelawareApplication September 1, 1931, Serial No. 560,620
In Germany September 1, 1930

3 Claims. (Cl. 18—8)

This invention relates to a process of and apparatus for forming artificial products.

In the process of and apparatus for spinning artificial products as disclosed in a German application of the same assignees of the present invention No. V. 71,30 filed on March 31, 1930 and laid open to the public on March 31, 1932, which consists entirely or partly of regenerated cellulose or cellulose derivates, especially viscose, 10 the products are formed by treatment in a setting bath and stretching the same over a considerable distance while still immersed therein. The product is then passed over an oscillating or reciprocating thread guide, around a godet wheel 15 and then downwardly into a horizontally rotating pot. By such process and arrangement a cake like thread body is obtained which can readily be treated and washed as well as wound off.

It has been discovered that artificial silk ribbons can be produced by utilizing, in part, this process.

It is therefore an object of this invention to provide a process and mechanism by which artificial silk ribbons can readily be produced.

25 A further object of this invention is to provide suitable mechanism to free the artificial silk ribbon from the tension imparted thereto by the spinning process.

These and other objects will become more apparent from a perusal of the following description and a study of the drawings in which:

Figure 1 is a diagrammatic view of a form of apparatus used in carrying out the process;

Figure 2 is a side elevation of the tension re-
35 moving means; and

Figure 3 is an end elevation of the same.

Referring now to the drawings, and more particularly to Figure 1, there is shown a diagrammatic view of the apparatus. The ribbon-like 40 artificial material having been spun into the pot 1, is washed and otherwise chemically treated. This may readily be accomplished by the loose winding imparted thereto as described above. It will be noted that the spinning pot comprises a 45 base portion, having perforations or openings 2 formed therein, resting on a plate 3 which is secured to a hollow axle 4. By this arrangement all of the treating liquids may easily be drained off.

50 After suitable treatment the pot is rotated and the ribbon of artificial silk is passed over suitable guide rods 5, 6 through an eyelet 7 made of glass or other suitable material and through a slotted opening 8 for a purpose to be hereinafter described, into a drying reel 9 where it is trans-

ported sideways during the drying operation which is accomplished by means of blowers 10. The ribbon is then reeled into a skein reel 11.

Referring now more particularly to Figures 2 and 3 there is shown in detail the construction 60 of the slotted opening 8. Due to the fact that, during the pot spinning process, a tension is imparted to the ribbon like material forming therein a series of twisted convolutions, it is necessary to provide means whereby the ribbons are 65 opened up completely, and smoothed. This is accomplished by providing between the spinning pot and the drying reel suitable mechanism which comprises an L-shaped brace 12, to the vertically extending portion of which is welded or other- 70 wise secured a horizontally extending arm 13 covered with rubber 14 pivotally supported to one end of the arm by means of a pintle 14 is a U-shaped bracket 15 through which the mem- 75 ber 16 is inserted. Secured to the pintle is a tongue like member 17 which is provided with a spring 18, which forcing the tongue against the member 16, resiliently holds the latter against the arm 13. The member 16 is likewise covered with rubber-like material. By the construction 80 it will be appreciated that the artificial silk ribbon is flattened and smoothed.

While the preferred practise of the process and the apparatus for carrying out the same have been described in detail, it is to be under- 85 stood that each may be widely varied without departing from the spirit of the invention or the spirit of the appended claims.

What I claim is:

1. A process for the manufacture of artificial 90 silk ribbons which comprises extruding the ribbon into a precipitating bath, collecting the same in a suitable receiver, washing and chemically treating the said ribbon while therein, and flattening and smoothing the said ribbons prior to 95 the drying thereof.

2. In combination, a spinning pot for collecting artificial silk ribbons, guide means, a ribbon flattening device through which the said ribbon is led from the guide means, and a drying reel 100 for receiving the said ribbon from the spinning pot.

3. In a process for the manufacture of ribbons of cellulosic material, the steps of extruding the ribbon, collecting and treating the same in a 105 rotating receptacle, reversing the motion of the receptacle, reeling the ribbon coming therefrom, at the same time flattening it.
